Primary Examiner — Sandra Snapp(74) *Attorney, Agent, or Firm* — McHale & Slavin, P.A.(57) **CLAIM**

The ornamental design for an expandable hose inlet coupler, as shown and described.

DESCRIPTION

FIG. 1 is a perspective view of the expandable hose inlet coupler of the instant invention;

FIG. 2 is a right view thereof;

FIG. 3 is a left side view thereof;

FIG. 4 is a bottom side view thereof;

FIG. 5 is a top side view thereof;

FIG. 6 is a first end view thereof; and,

FIG. 7 is a second end view thereof.

The broken lines illustrate the unclaimed hose and other matter and form no part of the claimed design.

1 Claim, 6 Drawing Sheets(56)
